ROSS HAZELRIGG Inventor

By E. O. Crooman,
Attorney

UNITED STATES PATENT OFFICE.

ROSS HAZELRIGG, OF ALAMEDA, CALIFORNIA.

COMBINED DOOR KNOB AND BELL.

1,009,512.

Specification of Letters Patent. Patented Nov. 21, 1911.

Application filed February 1, 1911, Serial No. 605,932. Renewed October 9, 1911. Serial No. 653,725.

To all whom it may concern:

Be it known that I, Ross HAZELRIGG, a citizen of the United States, residing at Alameda, in the county of Alameda and 5 State of California, have invented certain new and useful Improvements in Combined Door Knobs and Bells, of which the following is a specification.

This invention relates to door knobs, and 10 the principal object of the same is to provide a combined door knob and bell in which mechanism is arranged within the knob that is actuated by turning the knob to cause the bell to ring.

15 The invention contemplates a hollow knob formed in two sections, one being of bell metal, the knob inclosing bell ringing mechanism that is actuated by turning the knob, means being provided whereby the 20 said mechanism may be rendered inoperative, and means also being provided whereby the door connections of the knob can be manipulated so that the knob may be rotated without ringing the bell.

25 A preferred and practical embodiment of the invention is shown in the accompanying drawings, wherein:

Figure 1 is a view in elevation showing the improved knob attached to a door. 30 Fig. 2 is a view in front elevation, partly broken away, the bell section being removed. Fig. 3 is a view in rear elevation of the door plate showing the manner of attaching the knob thereto. Fig. 4 is an enlarged 35 vertical sectional view showing the knob fastened to a door plate. Fig. 5 is an enlarged vertical sectional view of the plate engaging sleeve of the knob.

Referring to the accompanying drawings 40 by numerals, it will be seen that the improved combined knob and bell comprises the door plate 6 provided with a transverse opening 7 in which the annular shoulder 8 is formed. A sleeve 9 provided with 45 external threads 10 has one end fitted within opening 7 and abuts shoulder 8 therein. A hook-shaped lip 11 projects from sleeve 9 and engages over the shoulder 8. An opening 12 extends longitudinally through sleeve 9 and its outer end communicates with a recess 13 formed in the flange 14 at the outer end of said sleeve. A latching rod 15 is rotatable in opening 12 and has a hook-shaped rear end 16 adapted for engagement over the shoulder 8. The forward end of rod 15 is equipped with an

angular handgrip 17 that lies in recess 13 and which can be manipulated to rotate rod 15 so that the end hook 16 will be disengaged from shoulder 8. A jam nut 18 is 60 carried by the threaded portion of sleeve 9 for binding engagement with plate 6 to prevent rotary movements of said sleeve.

A hollow section 19 has a sleeve extension 20, the end shoulder 21 of which abuts the end flange 14 of sleeve 9. A neck 22 projects from sleeve 20 and enters sleeve 9. The usual spindle 23 projects through plate 6, sleeve 9, neck 22 and sleeve 20 and is fastened to said sleeve 20 by the screw 24. 70

Sleeve 9 has an elongated strap extension 25 at its front end that extends through an opening 26 in the end shoulder of sleeve 20 and has its outer end bent to form a flange 27 that projects into an arc-shaped slot 28 75

in the plate 29 carried by the outer portion of knob section 19. Said plate 29 is flat and preferably integral with section 19 and forms the outer closure for said section. A pivot pin 30 connects a segmental rack 31 80 to said plate 29, said rack 31 being riveted, or otherwise fastened to the end flange 27 of strap 25. Adjacent the pivot pin 30, rack 31 carries a pair of oppositely disposed outstanding lugs 32 against which a 85

spring 33 bears, said spring being coiled about a pin 34 carried by plate 29 and having its rear arm 35 abutting a lug 36 so that the spring is held under tension. A rocker arm 37 is pivotally mounted on plate 29 and 90 its pointed end contacts with the teeth of rack 31 when the plate 29 is rotated. Said arm carries oppositely disposed lugs 38 which contact with the spring arm 39 which has a portion coiled about a pin 40 carried 95 by plate 29 and a rear arm 41 adapted to be engaged by a cam 42 pivotally mounted on said plate 29. Spring arm 39 carries a hammer 43.

A bridge 44 has its flanged ends 45 fastened to plate 29, and a hollow knob section 46, formed of bell metal, is fastened to the arch of said bridge by the screw 47. Pins 48 connect the bridge 44 to the knob section 46 so that pivotal movement of said section is prevented. Knob section 46 is provided with an edge recess 49 through which the cam 42 projects so that said cam can be manipulated to cause the same to contact with, or be removed from contact with, the 105 rear arm 41 of the hammer spring 39.

Normally the sleeve 9 is held immovable

relative to the plate 6 by the nut 18 and the strap 25 holds the rack 31 stationary. Sleeve 20 of knob section 19 is rotatable in sleeve 9 and the bell section 46 being rigidly fastened to section 19, it will be seen that when the knob is rotated, the arm 37 is oscillated by contact with the teeth of rack 31 so that lugs 38 are alternately forced against spring arm 39 so that said arm is vibrated and causes 10 the hammer 43 to strike the bell section and sound an alarm. The cam 42 normally places arm 39 under tension by being in contact with arm 41, and said cam projects through the recess in the bell 46. This arrangement permits the cam 42 to be rotated to disengage it from arm 41 so that the knob can be rotated without ringing the bell.

As has been stated, the sleeve 9 is locked to the door plate by the nut 18 to prevent 20 rotation of said sleeve and it will be clear that by manipulating said nut, the sleeve will rotate with the rest of the knob and the bell will not be rung.

It will be clear from the foregoing that 25 this invention provides simple means which normally sounds an alarm when the door is opened and when necessary or desirable, the alarm mechanism can be rendered inoperative by manipulating either the cam 42 or the nut 18. Obviously the cam is used by 30 the occupant when opening the door, and the nut is released when there is no necessity of the alarm being sounded.

What I claim is:—

- 35 1. A combined door knob and bell comprising a sleeve, means for fastening the same to a door plate, a knob section rotatably engaging said sleeve, said knob section having a plate at its outer end, said plate having a slot formed therein concentric to the axis of rotation of the knob sections an extension carried by said sleeve and passing through said section and entering said slot, a rack pivotally connected to said plate and fastened to said extension, a bell metal knob section, means for fastening the same to the plate on the first mentioned knob section, and bell ringing mechanism carried by said plate and actuated by said rack.
- 40 2. A combined door knob and bell comprising a door plate provided with an opening, a pair of hollow knob sections, means for rigidly connecting said sections, one of said sections constituting a bell, a sleeve rotatably engaged by one of said sections and provided with end hooks for engaging the inner end of said plate opening, means coacting with said hooks to lock the sleeve to said plate, bell sounding mechanism in-

closed by said sections, and means carried by 60 said sleeve for operating said mechanism.

3. A combined door knob and bell comprising a door plate provided with a shoulered opening, a sleeve having an end hook for engaging the shoulder of said opening, 65 manually operable means carried by said sleeve for engaging said shoulder, means carried by said sleeve and coacting with said engaging means for locking the sleeve to said plate against relative movement, and 70 combined knob and bell rotatably connected to said sleeve.

4. A combined door knob and bell, comprising a sleeve provided with means for engaging a door plate, said sleeve being provided with a longitudinal opening and a communicating end recess, a rod rotatable in said opening and having a hook at one end for engaging said plate and an operating handle at the other end that lies in said 75 recess, means for locking said sleeve to said plate to prevent relative movement thereof, and a combined knob and bell rotatably engaging said sleeve.

5. A combined door knob and bell comprising a sleeve, door plate engaging means carried thereby, said sleeve being externally threaded, a jam nut engaging said threads and coacting with said engaging means for locking the sleeve to a door plate, and a 90 combined knob and bell rotatably engaging said sleeve.

6. A combined knob and bell comprising a door engaging sleeve provided with an extension, a hollow section rotatably connected to said sleeve, said section being provided with a supporting plate, said plate being provided with a slot concentric to the axis of rotation of the knob section into which the said extension projects, a rack pivotally 100 connected to said plate and rigidly connected to said extension, said rack being provided with lugs, a spring carried by said plate and bearing against said lugs, a spring arm carried by said plate, a hammer carried 105 by said arm, an arm pivoted to said plate and engaging said rack, lugs carried by said arm for vibrating the hammer arm, a bell section fastened to the knob section and provided with an edge recess, and a cam 110 operable through said recess for controlling the operation of the hammer arm.

In testimony whereof I affix my signature in presence of two witnesses.

ROSS HAZELRIGG.
